CLAIM

I claim the ornamental design for a bottle cap, as shown and described.

DESCRIPTION

FIG. 1 is an upper, front left perspective view of a bottle cap for a bottle according to an embodiment;

FIG. 2 is a lower, front left perspective view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 2 Drawing Sheets
